CLAIM

I claim the ornamental design for a backless bra, as shown and described.

DESCRIPTION

FIG. 1 is a front and side perspective view of a backless bra, showing my new design;

FIG. 2 is a front elevational view thereof;

FIG. 3 is right side elevational view thereof, whereas the left side elevational view is a mirror image; and,

FIG. 4 is a rear elevational view thereof.

The broken lines shown in the drawings are for environmental structure only and form no part of the claimed design.
